UNITED STATES PATENT OFFICE.

HARLY L. HADLY, OF CHICAGO, ILLINOIS.

PAVED STRUCTURE.

Application filed December 8, 1920. Serial No. 429,192.

To all whom it may concern:

Be it known that I, HARLY L. HADLY, a citizen of the United States, residing at Chicago, in the county of Cook and State of Illinois, have invented certain new and useful Improvements in Paved Structures; and I do hereby declare the following to be a full, clear, and exact description of the invention, such as will enable others skilled in the art to which it appertains to make and use the same.

This invention relates to roadways and other paved structures, particularly to so-called highways adapted for miscellaneous vehicular and like traffic.

An object of the invention is to produce a hard, smooth surfaced roadbed, especially in districts where the soil is of clay, and it is a particular object to produce a road having a surface of fired, baked or dehydrated clay composed of adjacent brick-like prisms, preferably rectangular in horizontal section, having their exposed upper faces flush with respect to each other and presenting, as a whole, a smooth and even surface for traffic, said prisms being integrally united at their bases so that individual prisms are not likely to be pushed downward or displaced with respect to each other, the whole constituting an even, brick-like road surface susceptible of compensating for wide ranges of temperature without cracking, and sufficiently yielding, owing to the foundation of unfired or hydrated clay.

The invention comprises in general a paved structure having its upper layer shaped into an appropriate road surface and consisting of prisms separated from each other by narrow and relatively deep crevices, said upper layer consisting of hard, fired clay resting on a softer foundation of unbaked clay.

The invention further consists in the method of constructing said roadbed as more particularly set forth hereinafter and defined in the claims.

In the accompanying drawings:

Figure 1 represents, somewhat diagrammatically, a cross section of a roadway made in accordance with my invention;

Figure 2 represents a plan view thereof;

Figure 3 is a cross section illustrating, conventionally, cement tracks adapted for use on roads intended for heavy trucking;

Figure 4 is a plan view of the modifications shown in Figure 3.

Similar reference characters designate similar parts throughout the several views.

My invention is particularly adapted to be used in regions where the natural soil is of brick clay, although it is obvious that the invention is not limited to such regions since clay fillings may be treated in a similar manner to produce similar results. In Figure 1 of the drawings, the numeral 1 indicates a sub layer or foundation mass of hydrated or unfired clay such as may be found occurring naturally as a surface soil in certain regions, and numeral 2 indicates a surface layer of fired or dehydrated clay. The surface layer 2 is composed of a large number of adjacent prismatic bodies separated from each other laterally by narrow spaces 3. The spaces 3 may be tapered in vertical section. At their lower extremities the prismatic blocks are integrally united each block being an integral projection from a substratum or foundation mass of unbaked clay 1. It will be understood that the fired or baked clay layer and the unfired or unbaked foundation merge gradually into each other, the degree to which the clay is hardened by firing varying in proportion to the distance from an exposed surface so that between the hard completely fired exterior and the natural clay foundation is interposed a layer of clay fired to different degrees. It is preferred that the form of the said prismatic bodies shall be that of an ordinary brick with the longer dimension lying transverse of the roadway. The roadway may be of any desired surface configuration but it is preferably rounded according to approved practice, as illustrated.

In Figures 3 and 4 I have illustrated a roadbed of the same general type as that shown in Figures 1 and 2 and have adapted it to traffic of heavy trucks by providing tracks of cement or concrete properly spaced to provide for traffic in opposite directions. In Figures 3 and 4 the numerals 4—4 designate a pair of cement or concrete tracks provided for traffic in one direction and numerals 4^a—4^a designate similar tracks adapted for traffic in the opposite direction. These tracks are formed from solid bodies of concrete, cast in grooves 5—5, 5^a—5^a provided within the upper layer 2 of the roadbed. The said grooves may be enlarged slightly at their bottoms so that when the concrete is cast in them it will be interlocked or dovetailed with the hard clay.

layer. It will be obvious that said bodies of concrete may be reinforced with steel bars, if desired, in the ordinary manner of reinforcing concrete.

5 In building a roadbed according to this invention the surface clay is moistened with a sufficient quantity of water, smoothed and rounded, as by molding, to the appropriate configuration, *in situ*, and then the blocks 10 or prisms are carved in the surface layer by means of a sharp instrument pressed into the plastic layer in any suitable manner. The said blocks may be first marked out in squares or ovals or other shapes desired 15 and then the clay displaced or removed at the marked lines to the depth of four to eight inches, more or less, in order to separate the prismatic bodies from each other, leaving them, of course, united firmly to the 20 sub-soil or layer 1.

In case it is desired to make a roadbed like that shown in Figures 3 and 4, the grooves 5—5 and 5^a—5^a will be appropriately excavated, molded or otherwise shaped 25 by suitable tools.

After the roadbed has been suitably shaped and the blocks constituting its surface properly separated from each other heat will be applied to the surface *in situ* at 30 such temperatures and during such periods as may be necessary to fire the clay and turn it into a brick-like surface. In this firing operation the interstices between the blocks permit the heat to penetrate and fire 35 the layer 2 effectively. The firing process will obviously be more complete at the surface and adjacent the walls of the cracks or crevices than at the base or roots of said blocks where they are integrally united with 40 the sub soil 1 of unbaked clay.

In firing heat may be applied in any suitable manner. I contemplate building fires upon the surface so as to properly fire the 45 surface layer as desired, but it is obvious that travelling furnaces having suitable provisions for directing a hot blast down upon the surface may be used if found more convenient. In producing the road surface shown in Figures 3 and 4, a firing operation 50 similar to that set forth with respect to the forms shown in Figures 1 and 2 will be carried out after the roadbed has been properly formed and the grooves 5—5 and 5^a—5^a made. After firing the surface a suitable 55 concrete will be cast into the grooves formed therein either with or without first placing

suitable metal reinforcing means within said grooves. The surfaces of said tracks 4 thus formed will be smooth and shaped to a suitable configuration which may be a continuation of the surface of the layer 2, as indicated in Figure 3, or otherwise. 60

This construction, it will be obvious, is economical in those regions where the soil is of clay or where a suitable clay is abundant. By reason of the hard fired surface 65 layer formed of blocks which are independent of each other at their upper portions, but are integrally united by a partially fired layer, a smooth, hard surfaced roadbed will be formed that is not likely to be cracked by frost or by extremes of temperature, and is sufficiently yielding for its purposes. 70

If found desirable, after burning the 75 surface layer, the interstices may be grouted with loose sand, gravel or the like, or may be filled with wet Portland or like cement allowed to harden afterwards, or with an elastic substance such as asphalt, tar, 80 wooden wedges, or other materials possessing the desired properties.

Having described my invention in such manner as to enable those skilled in the art to which it appertains to make and use the 85 same, what I claim and desire to secure by Letters Patent of the United States is:

1. A roadway or other paved structure comprising a surface layer of fired clay, a 90 foundation of unfired clay, and a layer of partially fired clay uniting the surface layer with the foundation, said surface layer comprising adjacent prismatic bodies separated from each other laterally by narrow spaces and having their top surfaces substantially 95 flush with each other.

2. The process of making roadways or other paved structures which consists in molding *in situ* a suitable surface on a foundation of suitably moistened clay, 100 forming said surface layer into a multiplicity of adjacent prismatic bodies separated by intermediate spaces but united with the foundation mass of clay, and firing said surface layer. 105

3. The process of making roadways or other paved structures *in situ* which consists in molding a suitable surface on a foundation of suitably moistened clay and firing the surface of said molded clay. 110

In testimony whereof I affix my signature.
HARLY L. HADLY.
